UNITED STATES PATENT OFFICE.

ROY F. REDDING, OF EVANSVILLE, INDIANA.

METAL BED CONSTRUCTION.

1,373,763.

Specification of Letters Patent.

Patented Apr. 5, 1921.

Application filed July 8, 1920. Serial No. 394,754.

To all whom it may concern:

Be it known that I, ROY F. REDDING, a citizen of the United States of America, residing at Evansville, in the county of Vanderburgh, State of Indiana, have invented certain new and useful Improvements in Metal Bed Constructors, of which the following is a specification.

This invention has for its prime object 10 the provision of a member, commonly termed a "jaw," for supporting the metal side and end rails of beds, upon which the mattress springs rest, so constructed as to eliminate the necessity for casting an intermediate locking or any other device on the extremities of said side-rails as heretofore required, thus greatly reducing the cost of manufacture and preventing the breakage of parts which often resulted from the attempt to 20 fit such device to the companion element formed in the "jaw" heretofore used.

Figure 1 of the accompanying drawing is a top plan view of my improved "jaw" with the end and side rails connected therewith; Fig. 2 a side elevation; and Fig. 3 an end view with the side rail in section.

The "jaw" comprises a body portion 1 engaging the tube or post 2 at each corner of the bed and having an arm 3, a lug 4 and 30 an extension 5 beneath said lug.

By reference to Figs. 1 and 3 it will be noted that arm 3 is provided with a groove 6 forming a seat for the side-rail 7 which is secured by the projection therethrough of 35 a stud or bolt 8 having a threaded extremity for engagement by wing-nut 9. Said stud or bolt may be cast integral with arm 3, as shown, or the latter may be apertured for the passage therethrough of the side-rail retaining bolt or said rail may be secured by 40 a rivet in lieu of a stud or bolt.

Upon positioning the side-rail within groove 6 it will be observed that a portion thereof, namely, a corner of flange 7^a, rests 45 upon the top of lug 4, whereby the strain which would otherwise be imposed upon stud 8 is relieved and twisting or bending of said flange under excessive weight is prevented, and it will also be noted by reference to Fig. 3 that when the type of spring, as for 50 example a so-called "box-spring," desired by a purchaser necessitates the use of wooden or metal "slats," the side-rail is simply reversed, end for end, so that its flange 7^a will be disposed within groove 6 and a 55 corner of its lower flange 7^b will then rest upon extension 5 as shown in dotted outline.

The end-rail 10 is preferably secured to lug 4 by being so positioned with respect to the mold for the "jaw" as to be incased by 60 the metal poured for the formation of said lug.

It will, of course, be understood that two or more studs or bolts may be used for the retention of the side-rails should experience 65 prove that the single stud illustrated is insufficient and that other minor changes may be made from time to time without departure from the scope of the appended claims.

Having thus fully described the invention and its purpose, what I claim as new and desire to secure by Letters-Patent is:—

1. Metal bed construction comprising side-rails, a jaw secured to posts disposed at each corner of the bed, an arm extending 75 from said jaw, a lug projecting from said jaw opposite said arm adapted to support said rails, and means for detachably securing said rails to said arm.

2. Metal bed construction comprising 80 side-rails, a jaw secured to posts disposed at each corner of the bed, an arm extending from said jaw having a groove upon its inner surface for the reception of a portion of said rails, a lug projecting from said jaw 85 opposite said arm adapted to support said rails, and means for detachably securing said rails to said arm.

3. Metal bed construction comprising 90 side-rails, a jaw secured to posts disposed at each corner of the bed, an arm extending from said jaw, lugs projecting from said jaw substantially opposite the upper and lower edges of said arm adapted to support the upper or lower flange of said rails, and 95 means for detachably securing said rails to said arm.

4. Metal bed construction comprising 100 side-rails, a jaw secured to posts disposed at each corner of the bed, an arm extending from said jaw having a groove upon its inner surface for the reception of a portion of said rails, lugs projecting from said jaw substantially opposite the upper and lower edges of said arm adapted to support the 105 upper or lower flange of said rails, and means for detachably securing said rails to said arm.

ROY F. REDDING.
